[57] **CLAIM**

The ornamental design for a pusher roller unit, substantially as shown and described.

DESCRIPTION

FIG. 1 is a front elevational view of a pusher roller unit showing my new design;

FIG. 2 is a sectional view thereof, taken along the line II—II of FIG. 1;

FIG. 3 is a front perspective view thereof, the rear perspective view being a mirror image of that shown;
FIG. 4 is a top plan view thereof.

FIG. 1

FIG. 2

FIG. 3

FIG. 4
